IMPROVED CIGARETTE PACKAGE OPENER
AND CIGARETTE EJECTOR

Leroy V. Bell, Wakefield, R. I.

Application September 19, 1945, Serial No. 617,278

1 Claim. (Cl. 206—41.2)

1

This invention relates to an improved cigarette package opener and cigarette ejector.

An object of this invention is to provide a combination opener and ejector whereby upon manipulation thereof will automatically break the seal, open the package and eject the cigarettes therefrom.

Another object of this invention is to provide improvements in Patents 2,252,611 and 2,342,240 so that the package opener and package disclosed therein is made more practical and efficient from the manufacturing standpoint and the standpoint of the user, and provide a neater and more presentable package.

With these and other objects and advantages in view, the invention consists of the novel details of construction, arrangement and combination of parts more fully hereinafter described, claimed and illustrated in the accompanying drawings in which:

Figure 1 is a view of the three wrappers of a package in flattened out condition;

Figure 2 is the same of the opposite side of the wrapper;

Figure 3 is an elevational view partly broken away showing the ejector in position for operation after opening the package;

Figure 4 is a sectional view on the line 4—4 of Figure 1;

Figure 5 is an elevational view of the ejector;

Figure 6 is a sectional view on the line 6—6 of Figure 5;

Figure 7 is a perspective view of a package with the tab of the opener and ejector in position for operation thereof, and

Figure 8 is a modification of the invention.

Referring more in detail to the drawing, the reference numeral 10 generally designates the package which consists of an outside wrapper 12 the inner foil wrapper 14 and the inner wrapper 16 which package is in the usual manner covered with a Cellophane wrapping 18.

The outer wrapper 12 is provided with rectangular tabs 20 and 22, which project upwardly intermediate the upper ends thereof.

The tabs 20 and 22 are arranged to be superimposed by folding over upon each other and they are held in this position by an adhesive and the revenue stamp 24 which is secured by adhesive across the top of the package as indicated in the drawings in the usual manner.

It will be apparent from Figures 1 and 2 of the drawings that the upper part of the inside or innermost wrapper 16 has its upper edge projecting above the upper edge of the outside wrapper

2

12 on which the tabs 20 and 22 are located, that the projecting portion of the wrapper 16 is provided at the positions of the ends of the package with parallel fold lines 26 and 28 which are arranged vertically and at right angles with respect to a horizontal fold line 30 and that angulated fold lines 32 and 34 extending from the point of intersection of the fold lines 26, 28 and 30 meet at the point 36 which is coincident with the upper edge 37 of the inner wrapper 16. The described portions correspond to the right hand end of the top of the package.

Preparatory to closing the package and before all cigarettes for disposition therein have been disposed therein, the combination ejector and opener 38 is positioned in the package 10 as shown.

The ejector and opener 38 comprises the elongated leg of the tab 40 having the ejector portions 42 and 44 formed thereon, thus the ejector 20 may be formed so that three cigarettes can be ejected from the package at the same time, however, if it is desired to eject two cigarettes at a time the part 44 is cut on the line 48, or should it be desired to eject only one cigarette the ejector 25 42 is cut on the line 46. The package may therefore, be formed so that one or any number of cigarettes may be withdrawn by the pull tab.

The ejector portions are each bisected by a folding line 50 and the ends thereof are split to form the raised or foot portions 52 at the lower end thereof.

The tab 40 is bent downward at its outer end 35 and intermediate this end and the top of the package the tab is folded at 56, 58, 59 and 60. Thus, folded, the tab is adapted to be positioned over tabs 20 and 22 so that when the tab 40 is pulled, the package will be opened and the revenue stamp 24 will be destroyed, the inner wrapper 16 is provided with adhesive at 62 and 64 for holding 40 the overlap thereof over the folds of the tab, thus all of the wrappers are removed at the corner 45 of the package from which the cigarettes are to be removed.

In Figure 7, the tab extends beyond the folded edge of the Cellophane wrapper and this wrapper 45 will be opened as are the other wrappers of the package. In Figure 8, the tabs 20 and 22 have been replaced by a U-shaped tab 66 which has its ends secured to the outer wrapper by adhesive.

50 When it is desired to open the package, the package, as shown in Figure 7, is held in one hand and the tab 40 is pulled upwardly tearing the outer wrapper and revenue stamp. As pulling on the tab is continued it will break the wrapper 55 14 and tear along the near edge of the package

until the opposite end is open, and after the end is open, the tab 40 pulls the ejector 38 upwardly thereby drawing one, two or three cigarettes from the package. The tab 40 is connected to the ejector as shown in my prior Patent No. 2,342,240.

It is believed that the operation and structure of the combination opener and ejector will be understood by those skilled in the art and that modifications and changes may be resorted to without departing from the spirit of the invention or the scope of the appended claim.

Having thus described the invention, what is claimed as new and desired to be secured by Letters Patent is:

In a cigarette package, a comparatively thin rectangular-shape container including inner and outer wrappers and having a revenue stamp straddling one end, a pull tab positioned against the end of the package and extended under the revenue stamp, one end of said tab extending over the edge at one end of the package and downwardly against the outer surface of the end of the package, and an ejector comprising a vertically folded zig-zag strip carried by the opposite end of said tab and extended downwardly between cigarettes in the package and having an extended foot on the lower end that is positioned under

5 cigarettes in the package, said ejector and foot adapted to raise cigarettes from the package as the ejector is drawn upwardly by the tab, said ejector being connected to the tab by a plurality of folded sections, and said foot at the lower end of the ejector having a plurality of steps lying in a common plane with said steps located alternately on each side of said ejector strip at right angles thereto and integral therewith and each step positioned under a different cigarette, two panels of said folded strip and an integral step forming an ejector portion, and all of said portions except one being separable from said ejector.

LEROY V. BELL.
